CLAIM

The ornamental design for a cocktail strainer, as shown and described.

DESCRIPTION

FIG. 1 is a perspective view of the underside of a cocktail strainer, constructed in accordance with the present invention;

FIG. 2 is a second perspective view of the underside of a cocktail strainer of FIG. 1.

FIG. 3 is a perspective view of the topside of the cocktail strainer of FIG. 1;

FIG. 4 is an underside view of the cocktail strainer of FIG. 1;

FIG. 5 is a topside view of the cocktail strainer of FIG. 1;

FIG. 6 is a bottom edge view of the cocktail strainer of FIG. 1;

FIG. 7 is a top edge view of the cocktail strainer of FIG. 1; and,

FIG. 8 is a side edge view of the cocktail strainer of FIG. 1. The elements delineated in dashed or broken lines forms no part of the claimed design of the cocktail strainer.
